FOUNTAIN MARKER

Herbert W. Hempel and Walton C. Marsh, Belleville, Ill., assignors to Marsh Stencil Machine Company, Belleville, Ill., a corporation of Illinois

Application June 11, 1947, Serial No. 753,878

7 Claims. (Cl. 15—139)

1

This invention relates to improvements in fountain markers of the type wherein the marking fluid is fed to a marking tip.

An object of the invention is to provide an improved fountain marker in which the tip is removably mounted on the outer extremity of the valve stem in combination with a main reservoir and an absorption chamber controlled by the valve in such a manner that the marking fluid is accumulated in the absorption chamber around the upper end of the tip, from which it is absorbed into the body of the tip with provision for actuating the valve by pressure exerted on the tip in the marking operation.

A more specific object of the invention is to provide a simplified construction of a device of this type which may be economically manufactured and which may be readily assembled and disassembled for replacement of parts and for adjustment and cleaning.

Another specific object of the invention is to provide a device of the kind mentioned in which the tip is mounted in relation to the immediate accumulation of the marking fluid to permit the tip to be impregnated with the fluid in a gradual and uniform manner, whereby the marking extremity of the tip is kept uniformly saturated during the marking operation.

Additional advantages of the invention will be readily apparent from the following detailed description thereof taken in connection with the accompanying drawing, in which:

Fig. 1 is a vertical elevation of the assembled device with the protective cover cap removed;

Fig. 2 is an enlarged vertical section through the barrel or housing member with the valve and tip assembly shown in elevation;

Fig. 3 is an enlarged vertical section on the line 3—3 of Fig. 1;

Fig. 4 is an enlarged vertical section through the nose section of the device with the valve and tip assembly removed; and

Fig. 5 is a vertical elevation of the assembled device similar to Fig. 1, but with the cover cap in position.

In the embodiment of the invention illustrated in the drawing, the device is shown as including a barrel constituting the main marking fluid reservoir 10. The barrel is preferably in the form of an elongated hollow cylinder 11, the upper end of which is closed by a conical head 12. The lower end of the member 11 is internally threaded at 13, and is adapted to be associated with a nose piece 14 reamed out to form a cylindrical chamber 15 of approximately the same diameter as

2

the reservoir 10. The lower wall of the chamber 15 is bevelled forming a valve seat 16. Below the valve seat is an annular chamber 17 of somewhat reduced diameter with respect to the diameter of the chamber 15. Below the chamber 17 is a cylindrical bore 18 having a reduced diameter in respect to the diameter of the chamber 17. The lower end of the nose 14 has a reduced diameter in respect of the diameter of the upper portion of the nose piece, so that the nose piece terminates in the form of a truncated cone with the bore 18 arranged axially thereof. The upper end of the nose piece 14 is internally threaded at 19 and is removably connected with the barrel 11 by an externally threaded sleeve 20 adapted to cooperate with the threads 13 and 19 of the barrel 11 and of the nose 14, respectively. The upper end of the sleeve 20 has an annular wall 21 forming a central opening 22 that constitutes a guide for the upper end of the valve stem. The external wall of the sleeve 20 has a channel 23 intermediate of its length and a washer 24 is seated in the channel so that, when the nose piece and the barrel are connected, a tight joint will be formed between the lower edge of the barrel and the upper edge of the nose piece.

The valve assembly includes a valve stem 25 having a reduced extension 26 at its upper end and a threaded extension 27 at its lower end, as viewed in Fig. 3. The extremity of the lower end of the extension 27 is bevelled inwardly, forming a conical tip 28 to the extension 27. The wall of the valve stem 25 is enlarged to form a flange 29 below which and mounted on the valve stem is a valve plug 30 in the form of a washer with its lower end tapered to conform to the taper of the downwardly inclined valve seat 16 at the base of the chamber. The valve stem 25, with its extensions, is mounted for movement to open and close the valve 16, 30 by insertion of the extension 26 into the opening 22, which brings the lower extension of the valve stem 25 into the chamber 17 and maintains it axially in alignment with the axis of the bore 18.

The valve is actuated by an expansion spring 31 nested between the wall 21 of the sleeve 20 and the upper face of the flange 29. The spring 31 is of sufficient strength to normally close the valve 16, 30, but of a light enough tension so that endwise pressure on the valve stem will open the valve and permit flow of the marking fluid from the reservoir through the chamber 15 and into the chamber 17.

The marking tip is in the form of a cylindrical body 32 with a tapered bottom wall 33. The

upper wall of the tip is hollowed out to form a recess 34 so that, when the tip is mounted on threaded or serrated extension 27 of the valve stem 25, it will be retained against displacement, yet will be readily removable therefrom. It may be mounted either by threading it onto the threaded extension of the valve stem or pressing it into position over the serrations. The cylindrical section of the tip has substantial surface contact with the bore 18 which acts as a guide together with the opening 22 to hold the valve stem centered and to permit the sliding movement of the valve stem for operation of the valve 16, 30. This section of the tip also serves to restrict the flow from the chamber 17, causing the fluid to accumulate around the upper end of the tip.

An important feature of the invention is the provision of the absorption chamber 17 which, it will be noted by reference particularly to Fig. 3 of the drawing, has an internal diameter somewhat in excess of the upper cylindrical wall of the tip so that the tip is in contact with the marking fluid accumulated in the chamber 17 when communication with the main reservoir is established by the unseating of the valve 18, 30. This permits the marking fluid to be absorbed by the upper end of the tip, which fluid is then gradually absorbed into the body of the tip through which it percolates gradually and uniformly to the marking extremity 33 of the tip. The annular space between the external wall of the upper part of the tip and the inner wall of the chamber 17 is sufficient to submerge the upper end of the tip in the liquid accumulated in the chamber 17 and is also sufficient to accommodate for any expansion of the upper end of the tip to prevent binding and to permit free action of the tip when the valve stem is moved to and from its seat.

It will be understood that the valve assembly is designed so that normal pressure on the tip in the marking operation will be sufficient to overcome the resistance of the spring 31 so that, during the marking operation, communication between the main reservoir and the chamber 17 is established and maintained to insure the supplying of the marking fluid to the chamber 17 for absorption by the upper end of the tip. The upward movement of the valve stem is limited by the upper face of the flange contacting the bottom of the sleeve 20.

In the construction of the device, it is contemplated that the entire assembly shall be made of some light metal, preferably of aluminum, although not confined thereto, so that the marker may be readily carried in the pocket of the user.

In order to make the marker a convenient device to be thus carried, we prefer to add, as a part of the structure, a cover cap 35 which may be made of any suitable plastic material and in the form of a conical hollow member, as illustrated in Fig. 5. The internal diameter of the cap is dimensioned so that it will fit over the nose of the marker and enclose the nose end of the assembly.

From the foregoing description, it will be understood that the structure described will fully accomplish the objects hereinbefore set out, and that the parts may be economically fabricated, assembled and disassembled.

In filling the marker, it is only necessary to remove the nose section from the barrel and charge the barrel with the desired quantity of marking fluid, and then reconnect the nose with

the barrel by means of the threaded sleeve. The joint between the barrel and the nose is liquid sealed by the intermediate washer.

The device may be used in the marking operation by causing a slight pressure on the marking tip, thereby insuring the gradual and uniform flow of the marking fluid to the marking extremity of the tip.

While we have illustrated a specific embodiment of the invention, it is to be understood that the structure may be modified and that the invention consists of the structure and arrangement of parts combined in the manner herein-after defined in the claims.

What is claimed is:

1. A fountain marker comprising, in combination, a fluid containing supply reservoir, a chamber for receiving fluid therefrom from said reservoir, valve means for controlling flow of fluid from said reservoir to said chamber, a tubular extension from said chamber, the internal cross-sectional dimension of the extension being smaller than that of the chamber, and a fluid conducting marking tip connected to said valve means and extending from within said chamber slidably through and beyond said extension, said tip being in substantially fluid sealing engagement with the inside wall of said extension whereby fluid in the chamber is in contact only with the upper portion of said tip, said valve means being actuatable by pressure on said tip.

2. A fountain marker comprising, in combination, a fluid containing supply reservoir, an auxiliary chamber for receiving fluid therefrom from said reservoir, a valve including a valve stem between said reservoir and said chamber, a tubular extension from said chamber, the internal cross-sectional dimension of the extension being smaller than that of the chamber, an absorbent marking tip connected to said valve stem and having a portion thereof in closing engagement within said tubular extension and a portion extending into said chamber whereby the fluid in the chamber is in contact only with the upper portion of said tip, and means normally closing said valve responsive to pressure on said tip to open the same.

3. A fountain marker comprising, in combination, a fluid containing supply reservoir, an auxiliary chamber for receiving fluid from said reservoir, a valve seat between said reservoir and said chamber, a movable valve stem disposed axially of said valve seat and extending therethrough, a valve plug mounted for movement with said valve stem and engageable with said valve seat, a tubular extension from said auxiliary chamber, the internal cross-sectional dimension of the extension being smaller than that of the chamber, an absorbent marking tip connected to said valve stem and having a portion thereof in close fitting engagement within said tubular extension and a portion extending into said auxiliary chamber whereby the fluid in the chamber is in contact only with the upper portion of said tip, and means normally closing said valve responsive to pressure on said tip to open the same.

4. In a fountain marker, a fluid containing supply chamber, a second chamber, a valve seat between said supply chamber and said second chamber, a tubular extension of reduced internal cross-sectional dimension at the discharge end of said second chamber, a valve assembly including a valve stem and a valve plug for controlling the flow of liquid from said supply cham-

ber to said second chamber, and an absorbent marking tip mounted on said valve stem and having a portion thereof within said second chamber in spaced relation with the inner wall surface of the latter and a portion thereof mounted in close-fitting engagement with the inner wall surface of said tubular extension thereby restricting the flow from said second chamber to cause an accumulation of fluid therefor around the end of said tip within said second chamber.

5. In a device of the class described, a liquid containing supply barrel, a nose piece having an auxiliary chamber therein with a valve seat at its inlet end and an outlet opening of reduced size at its discharge end, releasable means for connecting said barrel and nose piece, a valve including a valve stem and a valve plug for controlling the flow of fluid from said barrel to said auxiliary chamber, and a marking tip of absorbent material removably attached to the lower end of the valve stem, said tip being of cylindrical shape and of a size to provide close-fitting engagement with said outlet opening, said tip having a portion thereof in absorbing relation with fluid in said auxiliary chamber and a portion mounted in the discharge opening from said chamber restricting the flow therethrough for all operating positions of the tip to cause an accumulation of fluid at the end of said tip remote from the marking surface thereof.

6. In a device of the class described, a fluid containing reservoir, a nose piece removably secured to an end thereof, said nose piece including a cylindrical-shaped chamber for receiving fluid from said reservoir and a cylindrical-shaped passageway between said chamber and the tip of the nose piece, the diameter of the passageway being smaller than the diameter of the chamber, movable valve means in the nose piece for controlling flow of fluid into the chamber, and an absorbent marking tip connected to said valve means for movement therewith, said tip being of approximately the same diameter as the passageway and slidably disposed therein so as to

extend into the chamber whereby only the surface of the upper portion of the tip within the chamber is directly exposed to fluid.

7. A fountain marker, comprising a fluid containing reservoir and a nose portion adjacent thereto; a chamber in the nose portion for receiving fluid from said reservoir; a passageway between the chamber and the tip of the nose portion, the transverse dimension of the passageway being less than that of the chamber; an absorbent marking tip having a transverse external dimension substantially equal to the transverse internal dimensional of the passageway slidably disposed in the passageway so that the upper portion thereof is positioned within the chamber and exposed to the fluid therein, the lower portion in the passageway restricting the free flow of fluid therethrough, the marking tip being movable between a retracted position and an extended position; and yieldable means urging the tip toward the extended position whereby when the tip is forced toward the retracted position the surface area of the tip in contact with the fluid in the chamber is increased.
